UNITED STATES PATENT OFFICE.

ELMER E. LUTZHOFF, OF JAMESTOWN, NEW YORK.

LID-SUPPORT.

1,378,591.

Specification of Letters Patent. Patented May 17, 1921.

Application filed June 21, 1920. Serial No. 390,562.

To all whom it may concern:

Be it known that I, ELMER E. LUTZHOFF, a citizen of the United States, residing at the city of Jamestown, in the county of Chautauqua and State of New York, have invented certain new and useful Improvements in Lid-Supports, of which the following, taken in connection with the accompanying drawings, is a specification.

10 The invention relates to supports for hinged lids of talking machines, upright pianos, chests and similar articles, in which the lid is swung upward and which it is desirable to support at different heights; 15 and the object of the improvement is to provide a simple and strong spring support by which the lid is firmly guided and poised in its upward and downward movement, and drops by gravity the last portion 20 of its closure, thereby insuring the release of all strain upon the lid while in the closed position, yet permitting the automatic taking-up of the spring support when the lid is raised, said spring support holding said 25 lid with an equalized counterbalance at any point throughout the arc of the movement of said raised lid until its gravity drops at the closure of the same; and the invention consists in the novel features and combinations 30 hereinafter set forth and claimed.

In the drawings, Figure 1 is a perspective view of the preferred form of the lid support in the closed position as attached to a portion of the cabinet of a talking machine; and Fig. 2 shows an elevation of the lid support holding the lid in the raised position, the cabinet being in section. Fig. 3 is a detail perspective view of the crescent shaped spring bell crank lever for the lid support. Fig. 4 is a sectional view at line 4-4 in Fig. 1 showing the construction and arrangement of the same. Fig. 5 is a sectional view of the case showing an elevation of a modification of the lid support 40 in the closed position, the raised position being shown in dotted outline. Fig. 6 is a perspective view of said modification of the preferred form of the lid support removed from the case in order to show the 45 conformation of the different parts; and Fig. 7 is a side elevation of said modified form with the parts in the raised position. Fig. 8 is a detailed perspective view of the 50 pivotal link with the flanged roller attached 55 as used in said modified form of the lid support.

Like characters of reference refer to corresponding parts in the several views.

The numeral 10 designates the case, cabinet or chest, and the numeral 11 the lid for 60 the same, which is hinged at 12 to the top of said case, cabinet or chest.

The support for the lid 11 preferably 65 comprises a plate 13 which has the vertical slot 14 therein to receive the flanged stud and roller 15 which works upward and downward in said slot 14. The plate 13 preferably has the lugs 16 which are attached to a slotted escutcheon or top plate 17, the slot 18 therein being of sufficient 70 length to allow the full action of the lid support bar 19 as the lid 11 is raised and lowered.

The lid support bar 19 has the flanged stud and roller 15 at its unattached lower 75 end and is hinged to the bracket 20 at its upper end, said bracket 20 being attached to the inner side of the lid 11 so that when said lid is raised, the support bar 19 forms a connective link between the roller and 80 stud 15 and the bracket piece 20 to hold the lid 11 at any desired point in the arc of its movement in raising the same.

The support bar 19 is controlled in its 85 supporting movement by means of the crescent shaped bell crank lever arm 21 though unattached to said arm, which arm 21 is hinged or pivotally attached at 22 to the plate 13, and has the short arm 23 with the stud 24 thereon to which is connected the 90 upper end of the spring 25, the lower end being preferably attached to a screw eye 26 which extends through the lug 27 on the lower end of the plate 13, which screw eye 26 has the thumb nut 28 to adjustably attach said screw eye to the lug 27, and thereby give the correct tension to the spring 25 and the bell crank lever 21.

The inner curved edge 29 of the crescent shaped lever 21 is shaped to receive and support the flanged roller 15 thereon at all points up and down the slot 14 bearing firmly underneath said roller by means of the comparatively stiff spring 25, the leverage of the crescent shaped or curved arm of the bell crank lever 21 being so proportioned to the arm 23 that the spring 25 supports the lid 11 at any point in its arc in raising and lowering the same until the moment of closure when the roller 15 passes onto the vertical 105 end 30 of said lever 21 and in consequence 110 drops by gravity upon the case 10. The

approach to said drop can be made as gradual as desired by the curve of the corner 31 leading from the upper edge 29 to the end 30 of said arm, since it is apparent that 5 the spring may thus be adjusted to gradually release the support of the lever 21 upon the roller 15.

As the lid is raised, the roller and stud 15 pass upward in the slot 14, the spring arm 10 21 following and pressing upward on the roller 15 to aid in raising said lid 11, supporting the same at any point above the corner 31 with an equalized pressure, that is, after the roller 15 has passed said corner 15 31 upon the upper edge 29 of the lever 21. The lever 21 follows the roller 15 until in the full raised position as shown in Fig. 2, said lever stands in the nearly horizontal position. It is apparent that complete control 20 and equalization are thus obtained for the lid 11 and that the same will be relieved of all strain when in the closed position.

The modification shown in Figs. 5-8 provides a slightly different shaped unslotted 25 supporting plate 32 for its coil spring 33, bell crank lever 34 with arm 35 and end 36 substantially the same, though in slightly different position from that shown in the preferred form in Figs. 1-4. A link arm 37 30 is pivotally attached at 38 to the lower end of the plate 32 and to the lower end of the support bar 40 at 39, thereby forming a toggle link support bar. A flanged roller 41 is provided on the link 37 which rides on 35 the upper edge 42 of the crescent shaped bell crank lever 34 in very much the same manner that the roller 15 rides on the edge 29 of the lever 21. It is apparent that the support bar 40 is free from, that is, unat- 40 tached to the bell crank lever 34, the only connection being the roller 41 as it rides on the upper edge 42 of the curved arm 35. The plate 32 has a stop 43 for the support bar 40 to limit the movement of the same and 45 the raising of the lid at the desired point, said support bar 40 having a pivotal attaching bracket 44 for attachment to the lid. The spring 33 is attached by means of a lug 45 and screw eye and thumb nut 46 to the 50 lower end of the plate 32 in substantially the same manner that the spring 25 is attached to the lug 27 in the preferred form. The plate 32 is turned to one side to decrease the length of the lid support.

55 It is apparent that the lid support mechanism shown in the modification attains a good purpose in much the same manner as the preferred form, but is not as simple and easy of manufacture as is the preferred form 60 in which the guide slot 14 holds all the parts firmly in alinement, yet permits their free action in controlling the raising and lowering of the lid 11.

65 It will be appreciated that when the lid 11 is in the raised position, there is substan-

tially no weight or leverage upon the lid support. As the lid is moved downward, the leverage increases rapidly with its consequent weight upon the lid support. Hence it is absolutely essential that the arm 21 or 70 36 of the ball crank lever should be shaped in a curve or crescent so that it will extend beneath and support the lower end of the support bar 19 or 40 in all positions until said support bar passes over the angle 31, 75 after which the lid will automatically drop by gravity as described. This gives a continuous support in all positions of said lid. In order to attain this essential purpose of a continuous support, the curved edge 29 of 80 the arm 21 is usually an off curve. If said arm 21 were straight, it is apparent that the roller 15 and support bar 19 with the lid would drop almost immediately after said arm 21 had left a substantially horizontal position, the lid and support bar being wedgingly forced downward and to one side by the roller 15. The curving of the arm 21 or 36 entirely overcomes this difficulty and supports the lid in all positions above the 85 angular point 31.

I claim as new:

1. In combination with a hinged lid, a supporting member movably connected to the lid, and a spring tensioned member arranged to lie in a substantially horizontal plane when the lid is open and to be moved downwardly by said supporting member upon closing of the lid, said spring tensioned member being formed with a curved 95 face and with a free end and said supporting member being arranged to ride on the curved face and then over said free end of the spring tensioned member when the supporting member is in down position. 100

2. In combination with a hinged lid, a supporting member movably connected to the lid, and a spring tensioned member having an upper face and a face at an angle to the upper face, the supporting member being formed to ride on the upper face and then ride on and engage the end face and to lie opposite the latter. 110

3. In combination with a hinged lid, a supporting member movably connected to the lid, and a spring tensioned member having a part arranged to lie approximately horizontal and to engage the first member in supporting relation and exert upward tension thereon when the lid is open and to exert lateral pressure only on the first member when the lid is closed. 115

4. The combination with a case or cabinet having a hinged lid of a support bar attached to said lid at its upper end and unattached at its lower end, and a spring bell crank lever arm support for said unattached lower end of said support bar in raising and lowering said lid. 125

5. The combination with a case or cabi- 130

net having a hinged lid of a support bar attached to said lid at its upper end and unattached at its lower end, and a crescent shaped spring bell crank lever arm support

5 for said unattached lower end of said support bar in raising and lowering said lid.

6. The combination with a case or cabinet having a hinged lid of a support bar hinged to said lid at its upper end, a roller

10 on the unattached lower end of said support bar, and a bell crank lever arm shaped to receive said roller on its upper side to support said lid in any position in raising and lowering the same.

15 7. The combination with a case or cabinet having a hinged lid of a support bar hinged to said lid at its upper end, a curved spring bell crank lever arm to support the lower end of said support bar in raising and 20 lowering said lid, and the lower end of said bell crank lever arm shaped to release said support and drop said lid by gravity in its final closure movement.

8. The combination with a case or cabinet 25 having a hinged lid of a support bar hinged to said lid at its upper end, a bell crank pivotally attached to said case having a crescent shaped arm so curved as to extend beneath the lower end of said support bar to support said lid in all positions 30 in raising and lowering the same, and a spring attached to the opposite arm of said bell crank lever to give tensional holding power to said crescent shaped arm to support said lid.

35 9. The combination with a case or cabinet having a hinged lid of a support bar hinged to said lid at its upper end, a bell crank pivotally attached to said case having a crescent shaped arm extending beneath the lower end of said support bar, a spring attached to the opposite arm of said bell crank lever to support said lid in all 40 positions in raising and lowering the same, said crescent shaped arm having a vertical end to permit closure of said lid by gravity

as said lower end of said bar passes off from said crescent shaped arm.

10. The combination with a case or cabinet 50 having a hinged lid of a support bar hinged to said lid at its upper end, a bell crank pivotally attached to said case having a crescent shaped arm extending beneath the lower end of said support bar, a spring attached to the opposite arm of said bell 55 crank lever to support said lid in all positions in raising and lowering the same, a roller connected to the lower end of said support bar, and means for guiding the same in raising and lowering said lid. 60

11. A lid support comprising a plate attached to the cabinet, a support bar having a roller thereon, a bell crank lever pivotally attached to said plate having a curved arm upon which said roller rides, a coil spring 65 attached to the other arm of said bell crank lever at one end and to said plate at the other with tensional adjustment therefor, the upper end of said support bar pivotally attached to said lid to support the same in 70 any position, and means on said plate to guide said roller in raising and lowering said lid.

12. A lid support comprising a plate having a vertical slot therein, a support bar 75 having a roller thereon slidably engaging in said slot, a bell crank lever pivotally attached to said plate having a crescent shaped arm upon which said roller rides, a coil spring attached to the other arm of said 80 bell crank at one end and to said plate at the other having adjusting means therefor, the upper end of said support bar pivotally attached to said lid to support said lid in any position in raising and lowering the 85 same.

In testimony whereof I have affixed my signature in the presence of two witnesses.

ELMER E. LUTZHOFF.
